UNITED STATES PATENT OFFICE

THOMAS A. EDISON, JR., OF EAST ORANGE, NEW JERSEY, ASSIGNOR TO THOMAS A. EDISON, INCORPORATED, OF WEST ORANGE, NEW JERSEY, A CORPORATION OF NEW JERSEY

DESIGN FOR A COOKING UTENSIL OR LIKE ARTICLE

Application filed May 20, 1933. Serial No. 48,170. Term of patent 3½ years.

To all whom it may concern:

Be it known, that I, THOMAS A. EDISON, JR., a citizen of the United States, and a resident of East Orange, in the county of Essex and State of New Jersey, have invented a new, original, and ornamental Design for a Cooking Utensil or Like Article, of which the following is a specification, reference being had to the accompanying drawing forming a part thereof.

In the drawing:

Figure 1 is a plan view of a cooking utensil or like article showing my new design;

Fig. 2 is a view in side elevation of the cooking utensil or like article; and

Fig. 3 is a view in elevation looking from the left in Fig. 2.

I claim:

The ornamental design for a cooking utensil or like article, substantially as shown.

THOMAS A. EDISON, JR.
